Inventor,

Joseph Mersman,
By Howard P. Smith,

Atty. Attorney

UNITED STATES PATENT OFFICE.

JOSEPH MERSMAN, OF OTTAWA, OHIO.

MEANS FOR INTENSIFYING REPRODUCED TONES.

Application filed January 10, 1922. Serial No. 528,155.

To all whom it may concern:

Be it known that I, JOSEPH MERSMAN, a citizen of the United States, residing in the town of Ottawa, in the county of Putnam and State of Ohio, have invented a certain new and useful Improvement in Means for Intensifying Reproduced Tones, of which the following is a specification.

The principal object of my invention is to provide new and improved means for intensifying reproduced tones, and to step by step harmonize all the different elements that enter into the recording, reproducing and amplifying of tone.

My invention makes it possible to construct the amplifying medium of the same material of which the diaphragm of the recording and reproducing device is constructed, whether it be mica, glass or some composition material. This insures harmony at every step from the recording of the record to the reproduction and amplification of the tone recorded.

Heretofore, a great deal of attention has been given to perfecting the reproducer of phonographs, but very little attention has been given to the creation of perfect harmony between the different elements that enter into the mechanical reproduction of tone.

The manufacturer of records in some cases will use a glass diaphragm in the recording device, and when the completed record reaches the dealer he will play it on a machine that has a mica diaphragm in the reproducer; and as it continues on its way, the reproduced sound passes into a wood or metal horn, all three steps being of a different nature and none of them alike as to sensitiveness. Accordingly, each will bring out the tone step by step differently from the original tone recorded. Therefore, in the confusion which results, tones that were originally recorded are lost, while others have been so changed that they issue in a harsh blasting manner. My invention overcomes all of the above objectionable features by producing a clear musical tone that is pleasing to the ear, and provided that the materials used are uniform, a reproduction is assured.

My invention consists in interposing in the path of the molecules of air set in motion by the reproducer, a device preferably of the same form as shown in the drawings, having sides composed of a sensitive mate-

rial that is preferably the same as that used in the diaphragm of the recording and reproducing device. This amplifying device may be round, square or of any other shape, ⁶⁰ and may be enclosed in a protecting tube or it may itself form the outside walls of the sound conducting means.

It is to be borne in mind that my improved amplifying means is different from ⁶⁵ all others in that it takes the place of, and does away with, that part usually known as the tone arm. Thus the tone waves act directly on the amplifier without passing through a tone arm and the usual neck or ⁷⁰ throat that is used in the ordinary phonograph. Sound waves which enter a neck or throat of wood, usually set up or produce inharmonious vibrations before those sound waves enter the amplifier proper. It is the ⁷⁵ object of this invention to eliminate everything that can in any way affect the tone vibrations adversely.

In the accompanying drawings, Figure 1 is a top plan view of the reproducer and ⁸⁰ the protecting tube, with the latter broken away to reveal the insertible amplifying device. Figure 2 is a side elevational view thereof. And Figure 3 is an end view of the amplifying device, protecting tube and ⁸⁵ shifting means.

Throughout the specification and drawings, similar reference characters denote corresponding parts.

In the accompanying drawings, the ⁹⁰ numeral 1 designates a turntable upon which there is mounted a record 2. Resting upon the latter is the stylus 3 of a sound box 4 that contains a reproducing diaphragm 5. The sound box 4 is connected by a hollow ⁹⁵ neck piece 6 to a resonating tube 7. The latter consists of a hollow cylinder constructed of any suitable material and preferably closed at its rear end by a head 8, and containing sound-emitting holes ¹⁰⁰ 8^a.

Adapted to be inserted in the resonating tube 7, which forms a protective cover for it, is an elongated frame 9 square in cross section, although it may be of any other suitable shape. This frame consists of two ¹⁰⁵ side members 10, 10 constructed of metal, although they may be made of mica or like material. These side members have grooved edge portions to receive top and bottom members 11, 11 preferably constructed of ¹¹⁰ the same material of which the diaphragm 5 is made, being in this instance mica. The

edge portions of the frame thus described are covered with longitudinal strips 12 of felt or other soft material to give said frame a relatively tight fit within the protecting tube 7.

For the purpose of shifting the frame 9 back and forth within the protecting tube 7 so as to increase or modify the tones emitted through the holes 8^a, the following means are provided. Formed in the wall of the protecting tube 7 is an elongated slot 13. Longitudinally movable through the latter is a pin 14 which projects outwardly from one of the sides 10 of the frame 9 and which is preferably covered with soft material to prevent rattling. The pin 14 has a large head that is adapted to be grasped by the fingers to shift the frame 9 to a desired position within the protecting tube 7. In those cases where it is desired to dispense with the insertible frame and make the walls of the tube 7 of mica, the neck piece 6 may be made to telescope into it to increase or lessen the tone as in the case of the shiftable amplifying frame.

Projecting downwardly from the middle portion of the resonating tube 7, is a lug 15 which is pivotally secured by a pin 16 to the upper portion of a supporting post 17. (See Figure 2.)

The amplifying frame which I have described and illustrated may be easily and economically manufactured, and insures a proper reproduction of the recorded tones. In other words, it insures harmony at every step from the recording of the tones to the reproduction and amplification of the tones recorded.

Having described my invention, I claim:

1. The combination with a reproducer, and a diaphragm, of a resonating tube communicating at one end with the reproducer, and a longitudinally positioned vibrator in the resonating tube of the same material as the diaphragm of the reproducer.

2. The combination with a sound box, a diaphragm in the sound box, and a resonating tube communicating at one end with the sound box, of a support in the resonating tube, and a plurality of parallel longitudinally positioned vibrators carried by the

support and of the same material as the diaphragm of the sound box.

3. The combination with a sound box, and a diaphragm in the sound box, of a resonating tube closed at one end and at its other end communicating with the sound box, said resonating tube having outlet orifices in its side walls adjacent its respective ends, and a longitudinally positioned vibrator of the same material as the diaphragm supported in the resonating tube between the sets of orifices.

4. The combination with a sound box, and a diaphragm in the sound box, of a resonating tube closed at one end and at its other end communicating with the sound box, said resonating tube having outlet orifices in its side walls adjacent its respective ends, a longitudinally adjustable support in the resonating tube between the sets of orifices, and a pair of vibrators mounted in the support and of the same material as the diaphragm.

5. The combination with a sound box, and a diaphragm in the sound box, of a resonating tube closed at one end and at its other end communicating with the sound box, said resonating tube having outlet orifices in its side walls adjacent its respective ends, a longitudinally adjustable support in the resonating tube between the sets of orifices, and a pair of vibrators mounted in the support and of the same material as the diaphragm, said resonating tube being circular in cross section and said support with the vibrators constituting a rectangular structure in cross section.

6. The combination of a diaphragm and a resonator comprising a tube, a plurality of vibrators mounted in the tube, said vibrators being formed of the same materials as the diaphragm.

7. The combination of a diaphragm formed of mica and a resonator comprising a tube, a plurality of mica vibrators located in spaced relation and longitudinally within the tube, and means for rigidly supporting the vibrators at their longitudinal edges.

In testimony whereof I have hereunto set my hand this 4th day of January, 1922.

JOSEPH MERSMAN.
